[57] CLAIM

An ornamental design for a transcutaneous electrical nerve stimulator pulse generator and power supply, as shown and described.

DESCRIPTION

FIG. 1 is a front elevation of a transcutaneous electrical nerve stimulator pulse generator and power supply showing our new design;

FIG. 2 is a bottom plan view thereof;

FIG. 3 is a right end elevation thereof;

FIG. 4 is a top plan view thereof;

FIG. 5 is a left end elevation thereof;

FIG. 6 is a rear elevation thereof;

FIG. 7 is a front elevation of a modified embodiment of the design illustrated in FIG. 1;

FIG. 8 is a top plan view thereof; and

FIG. 9 is a bottom plan view thereof.

Fig. 2.
